MERCURY VAPOR DISCHARGE DEVICE

Albert Frank Bowles and Harry M. Lipsius,
Philadelphia, Pa.

Application March 12, 1942, Serial No. 434,934

4 Claims. (Cl. 250—27.5)

The present invention relates to mercury vapor discharge devices and, more particularly, to a mercury arc rectifier provided with novel ignition means.

One object of our invention is to provide a mercury vapor arc rectifier of high ambient current temperature maintained through an electron flow from electrodes to vapor and vapor to electrodes through a primary ionization of the mercury vapor when the starting switch is thrown to the on position and maintained constantly until the operating switch or circuit breaker is thrown to the off position. Since it is well known that mercury vapor will not carry an electric current unless ionized, we have provided auxiliary mercury pools with a special wiring system as well as an electron filament at the top of the rectifier tube whereby the mercury in the auxiliary pools are first vaporized and while in the vapor phase the electron flow between the filaments and special heater elements bombard the mercury vapor and produce a high state of ionization and thereby produces a current flow between the anode elements of the rectifier and the cathode element supplying the positive electrical charge to the electrolytic cell or other apparatus requiring a controlled voltage and current in the output stage from the rectifier element.

A still further object of our invention is to provide a mercury vapor arc rectifier tube, embodying several features not heretofore embodied in any type of electric generator or rectifier heretofore known. It is well known that when a given voltage under a pressure of any given current is applied to the electrodes of a mercury vapor rectifier, there is a voltage drop or loss depending upon the type of material used in the electrodes, the distance between the anode and cathode elements, ambient temperature at which the rectifier is operated. Our experiments have proven that by producing a high electron bombardment of the vaporized mercury, whereby the mercury is ionized to a very high degree, thereby giving a cathode ray effect to the vaporized mercury, we have been able to reduce the operating losses to a large extent, as will be found in the following data tables, setting forth the voltage and current losses under various conditions of operation of our mercury vapor rectifier.

Potential drop or loss with operating characteristics of our mercury vapor arc rectifier with electron filament and auxiliary pool vapor-

izer and starting electrodes, operated at 50° C. and 96 percent transformer efficiency:

Table I

Distance between electrodes Mm.	Potential drop across the—			Overall potential drop
	Anode	Cathode	Spark-gap	
40	3.0	5.0	1.4	9.4
50	2.55	5.0	1.35	8.9
55	2.0	3.0	2.0	7.0
60	2.5	4.3	1.65	8.45
65	3.0	5.5	1.9	10.4
70	3.3	6.0	2.6	11.9
75	4.5	7.2	3.5	14.85
80	4.75	8.0	3.75	16.50

It will be observed that the potential loss between electrodes and spark gap is controllable by means of the adjustable anodes and the main mercury pool to an overall potential loss of less than 10 percent of the operating load.

These and other objects which will appear more clearly as the specification proceeds, are accomplished according to our invention, by means of the combination of elements set forth and claimed hereinafter.

A typical installation according to our invention is set forth in the following detailed description, defined in the appended claims, and illustratively exemplified in the accompanying drawing in which:

The single figure is a diagrammatic and schematic view of a mercury vapor rectifier unit, showing the electrode system, transformer and reactance system for straightening the sine curve or cycles to give a line equivalent to that produced by a motor generator set.

Referring now to the drawing, the mercury vapor rectifier is composed of the tank or tube 28, which may be of any desired size from 3 to twenty four inches in diameter and from 5 to thirty inches deep or high. This shell for the mercury vapor rectifier may be manufactured from a special heat resistance glass such as pyrex, pyrex-quartz mixture or quartz, or a glass lined metal shell. The water jacket 83 provides a cooling system by which the ambient temperature within the rectifier shell can be maintained at any desired degree. In currents of from 800 to 1500 amperes the rate at which water is delivered to and taken from the rectifier shell will approximate 3 gallons per minute. At currents of from 1600 to 5,000 amperes the rate of water passed through the cooling jacket or coils will amount to 5 gallons per minute. Higher currents

will require a slight increase in water passage for cooling purposes. The transformer 63 is composed of a number of sections of laminated steel sheets of transformer grade 29 gauge number .0141. The amount of the iron in the transformer depends upon the voltage and current desired in the secondary leads. It is pointed out that several taps *a*—*h* are taken from the secondary coil of the transformer 63 by which, through the conductors 65, 66, any desired alternating current may be taken across the reactance coils 71, 72, 73 and 74. As an example of the transformer winding for a step down type, we impress a voltage of 440 A. C. volts across the transformer 63 through primary winding of the transformer. Using 1 volt per turn of the winding, and allowing additional copper or turns for normal loss, we take a total of 450 turns on the primary side of the transformer 63. On the secondary side of the transformer 50 turns are provided, equally spaced so that taps taken at each 5th turn will provide any desired voltage for impressing upon the induction or reactance coils. Assuming that the 440 volts A. C., are delivered at 80 amperes current we obtain from the secondary side of the transformer 800 amperes.

When alternating current is supplied to the transformer 63 through the leads 63*a*, a heating current is delivered through the leads 68, 70 and 68₁, 70₁ to the heating coils 69_a, 69_{a1} arranged to heat the auxiliary mercury pools 69, 69₁ at the bottom of the rectifier tube 28, and through leads 76, 77 to the special filament 84 at the top of the rectifier tube. The special filament 84 is arranged in front of a reflector 84*a* forcing the electrons given off to flow toward the opposite end of the tube 28. When the heater circuit is established the small auxiliary pools of mercury 69, 69₁ are quickly vaporized. The filament 84 immediately begins throwing off electrons which bombard the mercury vapor evaporated from the pools in 69, 69₁ and this vapor becomes heavily ionized. When this mercury vapor becomes ionized it then makes contact between the cathode 82 disposed in the main mercury pool 81 and the anodes 78—78. When such electric contact is made with the consequent flow of current between the anodes 78—78 and the cathode 82, a relay 67 operates which opens the heater circuit thereby cutting off the current flow in 76—77 and 68, 70, 68₁, 70₁. Water is then introduced through 85 and 83 at such rate that the temperature within the jacket is maintained between 50° C. and 75° C. depending upon distance between the electrodes 78 and 81. By raising and lowering the anodes 78—78 the voltage drop between the anodes 78 and cathode 82 is increased or decreased in direct proportion to the mean distance between the spark gap. In practice it is well known that the voltage drop across the cathode varies between 9 and 6 volts. The voltage drop across the anodes varies between 2 and 5 volts. The voltage drop across the mercury vapor arc varies from .05 to 0.2 volt per centimeter distance between the electrodes. These voltage drops across the electrodes and the arc gap have been determined for the conventional type of mercury vapor rectifier where the contact between the mercury and electrodes is brought about in the shaker type of rectifier. Our experiments have shown that where the mercury vapor within the rectifier shell is highly ionized, that the voltage drop across the anodes and cathodes varies directly as the square of the

distance between the electrodes and directly with the electrode materials used. The following table shows the voltage drops plotted for the various materials which we have used in constructing the anodes and cathodes in our mercury vapor rectifier:

Table II

	Electrode material	Voltage drop
10	Silver.....	0.5
	Copper.....	10.2
	Platinum.....	1.8
	Platinum-tungsten.....	2.3
15	Carbon-steel highly polished.....	2.5
	Carbon (graphite).....	9.6
	Silicon carbide steel highly polished.....	6.4

The electrodes were all highly polished, and of $\frac{3}{8}$ inch diameter and from 4 to 6 inches long. The spark gap between apex of anode and cathode was maintained at 60 mm. From this we were able to determine the exact voltage drop between the anodes and cathodes by raising and lowering the distance from anode to cathode.

After the water has been introduced as a coolant through the water jacket 83 of the rectifier shell 28, and the current flow between anodes 78 and cathode 82 has been established the field rheostat 87 of the dual plate type to which the leads 65 and 66 are attached before passing through the rectifier 28, is then adjusted by means of the hand operated knobs 88 so that the voltage across the rectifier plus the drop will be between 4.5 and 3.56 volts, while the current delivered will vary between 600 and 2000 amperes, as desired.

The electrodes 78—78 are adjustable so that they may be raised or lowered to give any desired drop across the terminals 78 and 81 of the rectifier.

40 We have found that by providing two auxiliary pools at 69, 69₁ the menisci of the mercury contained in the auxiliary wells will make a contact with the meniscus of the main mercury pool in 82 holding the cathode element of the rectifier, so that when current is supplied to the transformer, the mercury in the auxiliary pools 69, 69₁ is vaporized, while the electron filament 84 begins throwing off electrons and a bombardment of the mercury vapor takes place. This electron bombardment produces a highly ionized mercury which is capable of carrying current and thereby completes the circuit between the anodes 78 and the cathode 82 of the rectifier system, with the smallest possible voltage drop or loss between the electrodes. The energized vapor establishes a physical contact between the electrodes 78 and the auxiliary pools 69, 69₁. Since the auxiliary pools 69, 69₁ make physical contact with the main pool 81 through the mercury menisci of the auxiliary pools an electric current and voltage flow is set up between the electrodes 78 and 82 by means of the ionized mercury vapor, this voltage flow between the anodes 78 and cathode 82 operating the relay 67 to throw the heating filaments out of circuit.

65 We claim:

1. A mercury vapor discharge device comprising a sealed bulb, an anode projecting into said bulb, a mercury pool cathode disposed in said bulb opposite said anode at a distance therefrom sufficient to prevent arcback, means to connect said anode and cathode, respectively, to opposite terminals of a source of high potential current, an auxiliary relatively small mercury pool adjacent the mercury pool cathode, means for heat-

ing the mercury in said auxiliary pool to a temperature to cause evaporation of the mercury, an electron emitting element disposed at the anode end of the bulb and consisting of a coil of wire made of an alloy capable of emitting electrons at high temperatures, means for connecting said electron emitting coil across a source of high intensity low voltage current, and means for breaking the circuit through said electron emitting coil as soon as a current flows from the anode to the cathode.

2. A mercury vapor discharge device, as claimed in claim 1, including a reflector arranged behind said electron emitting coil to concentrate the electrons emitted therefrom upon the mercury vapors produced from the mercury in said auxiliary pool.

3. A mercury vapor discharge device, as claimed in claim 1, in which said heating means for the mercury in said auxiliary pool includes a heating coil, means to connect said heating coil across a source of high intensity low voltage current, and means for breaking the circuit through said heating coil, as soon as a current flows from the anode to the cathode.

4. A mercury vapor arc rectifier, comprising a sealed bulb, a pair of anodes projecting into said bulb from one end thereof, a mercury pool cathode disposed in said bulb opposite said anodes at a distance therefrom sufficient to prevent arcback, means to connect said anodes, respectively, to opposite terminals of a source of high potential alternating current, means to connect said cathode over a load to the zero point of said source of high potential alternating current, an auxiliary relatively small mercury pool adjacent said mercury pool cathode, means for heating the mercury in said auxiliary pool to a temperature to cause evaporation of the mercury, an electron emitting coil of an alloy capable of emitting electrons at high temperatures disposed at the anode end of the bulb, means for connecting said electron emitting coil across a source of high intensity low voltage current, and means for breaking the circuit through said electron emitting coil as soon as a current flows from the anodes to the cathode.
